SEWING MACHINE

Andrew B. Clayton, Union, N. J., assignor to The
Singer Manufacturing Company, Elizabeth,
N. J., a corporation of New Jersey

Application November 1, 1932. Serial No. 640,586

9 Claims. (Cl. 112—63)

This invention relates to sewing machines, more particularly of the feed-off-arm type, and has for an object to provide a machine of this type having a simplified form of frame and work-supporting arm with a simple and efficient chain-stitch looper mechanism and an accompanying looper-thread controlling mechanism constructed for, arranged in and combined with said work-supporting arm to form a simple and efficient high speed chain-stitch feed-off-arm sewing machine.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front elevation, partly in section, of a feed-off-arm sewing machine embodying the invention. Fig. 2 is a top plan view of the machine with the head of the free end of the gooseneck broken away to show the parts in the underlying free end of the work-supporting arm. Fig. 3 is an end elevation of the machine looking from the left in Figs. 1 and 2, with the work-supporting arm in longitudinal vertical section. Fig. 4 is a section on the line 4—4, Fig. 2. Fig. 5 is a section on the line 5—5, Fig. 2. Fig. 6 is a section on the line 6—6, Fig. 2. Fig. 7 is a section on the line 7—7, Fig. 2. Fig. 8 is a section on the line 8—8, Fig. 2 to show the feed-bar actuating mechanism, and Fig. 9 is a front elevation of the lower forwardly disposed arm which is shown in section in Fig. 1.

The machine frame includes the usual gooseneck 1 which terminates at its free end in the head 2 carrying the reciprocating needle-bar 3 and presser-bar 4 fitted, respectively, with the needles 5 and presser-foot 6. The needle-bar 3 is reciprocated by means of the usual link-connection 7 with the crank 8 on the rotary shaft 9 which is journaled in the horizontal member of the gooseneck 1 and is fitted with the usual balance wheel 10 and pulley 11 for belt-connection with the source of power. The needle-bar 3 carries the needle-thread take-up arm 12 commonly used in chain-stitch sewing machines. Except for the chain-stitch type of take-up arm 12, the present gooseneck and its mechanism are preferably constructed substantially in accordance with the disclosure of the application of Walter Myers, Serial No. 627,409; filed Aug. 4, 1932. The inven-

tion is not to be understood, however, as limited in any way to the specific construction of the gooseneck and/or the mechanism carried thereby.

The gooseneck is rigidly associated with and preferably mounted on a preferably U-shaped bed including an arm 13 extending forwardly from the gooseneck, a laterally extending hollow horizontal arm 14 joined at one end to the forwardly extending arm 13, and a rearwardly extending hollow horizontal work-supporting arm 15 joined at one end to and coplanar with the laterally extending arm 14 and terminating at its free end below the head 2 at the free end of the gooseneck. The arms 14 and 15 are joined in the form of an L laid horizontally.

There is journaled in the forwardly disposed laterally extending arm 14 a lower rotary shaft 16 which is connected to rotate in timed relation with the shaft 9 preferably by the conventional clip-belt 17 housed within the belt-casing 18 exteriorly of the sewing machine frame proper.

The machine may be provided with feeding mechanism including a feed-bar 19 disposed centrally within and lengthwise of the work-supporting arm 15. The feed-bar 19 is mounted to rock with and slide upon the fulcrum-block 20 mounted on the eccentric fulcrum-pin 21 sustained by and rotatably adjustable in the spaced feed-fulcrum-posts 22. The feed-bar 19 carries the feed-dog 23. The feed-bar is provided at its forward end, i. e., its end remote from the feed-dog 23, with a horizontal feed-lift fork 24 and a vertical feed-advance fork 25, Fig. 8. These forks embrace, respectively, the feed-lift eccentric 26 and feed-advance eccentric 27 on the shaft 16.

Journaled in bearing lugs 28, 29, within the work-supporting arm 15 is the rocking and sliding looper-shaft 30 carrying the threaded loopers 31 which cooperate with the needles 5 to form the usual two-thread or double-chain stitches. The looper-shaft 30 is given its rocking movement, to move the loopers endwise into and out of the needle-loops, by means of the eccentric 32, Fig. 4, on the lower rotary shaft 16. The eccentric 32 is embraced by the follower 33 which slidably engages the pin-extension 34 of a rock-lever 35 fulcrumed at 36 within the work-supporting arm 15 and connected by the link 37 to the crank-arm 38 fixed upon the looper-shaft 30.

The looper-shaft is given its endwise sliding movements, to give to the looper blades their usual sidewise components of motion, by means of the eccentric 39 fixed on the shaft 16. The eccentric 39 is embraced by the split block 40

working in the vertical fork 41 at the forward end of a slide-rod 42 journaled in the bearing 43. Fixed to the rearward end of the slide-rod 42 is a lateral arm 44 forked to embrace the looper shaft 30 between the hub 38' of the crank-arm 38 and the collar 45.

The lever 35 and slide-rod 42 extend substantially horizontally from the laterally extending arm 14 into and longitudinally of the work-supporting arm 15. The lever 35 and slide-rod 42 constitute a pair of intermediate looper-shaft actuating elements which are actuated, respectively, by the eccentrics 33 and 39 and extend substantially horizontally from the latter into and lengthwise of the work-supporting arm.

The feed-bar 19 with its actuating eccentrics 26, 27 are preferably arranged substantially centrally of the work-supporting arm, to minimize torsional strains on the feed-bar. The looper actuating eccentrics are preferably arranged at opposite sides of the feed eccentrics 26, 27, to facilitate their connection with the looper-shaft 30 by means of the intermediate connection elements 35, 42 previously described.

The laterally extending arm 14 is formed preferably at its juncture with the forwardly extending arm 13 with an opening 46 within which and upon the shaft 16 is preferably mounted the looper-thread-controlling cam 47. This cam may be of usual form to cooperate in the usual manner with the stripper blade 48 and the thread-guides 49. An intermittent thread-nipper 50 may also be arranged alongside the thread-controller cam 47, Fig. 2, to function as usual to nip the looper-thread at the time when the cam 47 is pulling slack looper-thread back from the loopers during the retracting stroke of the latter following seizure of the needle-loops. The nipper is opened as the loopers advance, so that the looper-thread may run freely from the supply and the usual looper-thread-tension device 51 which may conveniently be mounted on the belt-casing 18.

From the thread-controller 47, the looper-threads may run in the groove 52 cut externally along the laterally extending arm 14 to the thread-tube 53 through which the looper threads may run to the stationary guide 54 adjacent the heels of the loopers. The thread-controller opening 46 in the arm 14 may normally be closed by the hinged cover 55 which may be swung upwardly about its hinge pin 56 to expose the thread-controller.

Having thus set forth the nature of the invention, what I claim herein is:—

1. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocatory needle mounted at the free end of said gooseneck and connected to be driven by said upper rotary shaft, and an oscillatory chain-stitch looper disposed within the free end of said work-supporting arm in cooperative relation with said

needle and connected to be driven by said lower rotary shaft.

2. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocatory needle mounted at the free end of said gooseneck and connected to be driven by said upper rotary shaft, a four-motion chain-stitch looper mounted within the free end of said work-supporting arm in cooperative relation with said needle, and means connected to said lower rotary shaft and extending substantially horizontally from said laterally extending arm into said work-supporting arm for actuating said looper.

3. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocatory needle mounted at the free end of said gooseneck and connected to be driven by said upper rotary shaft, a four-motion chain-stitch looper mounted within the free end of said work-supporting arm in cooperative relation with said needle, means connected to said lower rotary shaft and extending substantially horizontally from said laterally extending arm into said work-supporting arm for imparting endwise loop-seizing and -shedding movements to said looper, and other means connected to said lower rotary shaft and extending substantially horizontally from said laterally extending arm into said work-supporting arm for imparting sidewise movements to said looper.

4. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocatory needle mounted at the free end of said gooseneck and connected to be driven by said upper rotary shaft, a rocking and sliding looper shaft journaled within and lengthwise of said work-supporting arm, a looper carried by said looper-shaft within the free end of said work-supporting arm in cooperative relation with said needle, an eccentric on said lower rotary shaft and connections

- for imparting endwise sliding movements to said looper-shaft, a second eccentric on said lower rotary shaft, a vibratory lever actuated by said eccentric and fulcrumed within said work-supporting arm so as to extend lengthwise of the latter, and an operative connection between said vibratory lever and said looper-shaft for imparting rocking movements to the latter. 80
5. A chain-stitch feed-off-arm sewing machine having, in combination, a frame including a gooseneck, a forwardly extending arm rigid with said gooseneck, a second arm extending laterally from the forward end of said first mentioned arm, a work-supporting arm extending rearwardly from and substantially coplanar with said laterally extending arm, a reciprocating needle operatively mounted in said gooseneck, a rotary shaft journaled in said laterally extending arm, a feed-bar disposed within and lengthwise of said work-supporting arm, a looper-shaft journaled within and lengthwise of said work-supporting arm below said feed-bar, feed-actuating means on said rotary shaft connected to operate said feed-bar, a pair of looper-actuating eccentrics on said rotary shaft at opposite sides of said feed-actuating means, a slide-shaft connected to one of said eccentrics and to said looper-shaft for moving the latter endwise, a rock-lever connected to the other of said eccentrics and to said looper-shaft for rocking the latter, said slide-shaft and rock-lever being mounted within and lengthwise of said work-supporting arm and at opposite sides of said feed-bar. 90
6. The combination with a hollow horizontal work-supporting arm and a hollow horizontal forwardly disposed arm substantially coplanar with and carrying said work-supporting arm, said arms taken together having the form of an L, of a rotary driving shaft journaled in said forwardly disposed arm, a rocking and sliding looper-shaft journaled in said work-supporting arm, a pair of eccentrics on said rotary shaft, a pair of intermediate looper-shaft actuating elements actuated, respectively, by said eccentrics and extending horizontally from the latter into and lengthwise of said work-supporting arm, and means operatively connecting said elements, respectively, to said looper-shaft to impart to the latter its rocking and sliding movements. 100
7. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocating needle mounted at the free end of said gooseneck and connected to be driven by said upper rotary shaft, a thread-carrying chain-stitch looper disposed within the free end of said work-supporting arm, means connected to said lower rotary shaft and extending substantially horizontally from said laterally extending arm into said work-supporting arm for actuating said looper, and a looper-thread-controller mounted on said lower rotary shaft within said laterally extending arm. 110
8. A chain-stitch feed-off-arm sewing machine having, in combination, a frame including a gooseneck, a forwardly extending arm rigid with said gooseneck, a laterally extending horizontal arm joined at one end to said forwardly extending arm, a rearwardly extending horizontal work-supporting arm joined at one end to and substantially coplanar with said laterally extending arm and terminating at its free end below the free end of said gooseneck, an upper rotary shaft journaled horizontally in said gooseneck, a lower rotary shaft journaled in said laterally extending arm, means connecting said shafts to rotate in timed relation to one another, a reciprocating needle mounted at the free end of said gooseneck and connected to be driven by said upper rotary shaft, a thread-carrying chain-stitch looper disposed within the free end of said work-supporting arm, means connected to said lower rotary shaft and extending substantially horizontally from said laterally extending arm into said work-supporting arm for actuating said looper, and a looper-thread-controller mounted on said lower rotary shaft within said laterally extending arm. 120
9. The combination with a hollow horizontal work-supporting arm and a hollow horizontal forwardly disposed arm substantially coplanar with and carrying said work-supporting arm, said arms taken together having the form of an L, of a rotary driving shaft journaled in said forwardly disposed arm, a rocking and sliding looper-shaft journaled in said work-supporting arm, a pair of eccentrics on said rotary shaft, a rock-lever within the work-supporting arm connected to be actuated by one of said eccentrics, a crank on said looper-shaft operatively connected to said rock-lever, a slide-rod within the work-supporting arm connected to be actuated by the other of said eccentrics, and means connecting said slide-rod to said looper-shaft to move the latter endwise. 130
